VENETIAN BLIND HOLD-DOWN ARRANGEMENT

Joseph A. Anderle, Westerleigh, N.Y., assignor to Lorentzen Hardware Mfg. Corp., Hoboken, N.J., a corporation of New York

Application August 16, 1955, Serial No. 528,693

5 Claims. (Cl. 160—178)

This invention relates to Venetian blinds, and more particularly to a hold-down bracket for engaging the bottom bar of a Venetian blind to prevent the blind from swaying.

Venetian blinds are subject to swaying due to wind, so that the slats and bottom bar strike against the window, or jamb, making an objectionable noise, scarring the paint, and sometimes even bending the slats. A similar problem is encountered when a Venetian blind is mounted on a door. Hold-down brackets are sometimes used to prevent swaying of the blind, a hold-down bracket installation consisting of a bracket mounted on the door or on the window frame adjacent each end of the bottom bar.

Usually, a gudgeon pin protruding from each end of the bottom bar is engaged within a hookline portion of each hold-down bracket to hold the ladder tapes of the blind more or less taut and thereby prevent swaying of the blind. Many hold-down brackets have had downwardly opening, hook-shaped portions for receiving the gudgeon pin, it being necessary to depress the bottom bar slightly so as to stretch the ladder tapes a little while entering the gudgeon pins within the hold-down brackets. Upon releasing the bottom bar, the normal resilience of the ladder tapes biases the bar and gudgeon pins upwardly with the gudgeon pins being received within the downwardly-opening hooklike portions of the hold-down brackets to prevent fortuitous disengagement of the gudgeon pins from the brackets. A typical hold-down bracket installation of this type is disclosed in Lorentzen Patent 2,298,892 of October 13, 1942.

In closing a Venetian blind, the slats of the blind are simultaneously tilted by the ladder tapes which are suspended from a tilt member extending longitudinally along the top of the blind. In enclosed metal head constructions, such as that shown in Nelson Patent 2,455,135 of November 30, 1948, the tilt member consists of tape rockers mounted on a tilt rod that extends within a channel-shaped metal headbar. Regardless of the particular type of tilt member employed, the slats are tilted by raising the ladder tape branches on one face of the blind and dropping the tape branches on the other face of the blind. As the slats of the blind approach fully closed position, there is a tendency for the ladder tape branches that are being raised to be wound up about the tilt member to some degree, thus bodily raising the ladder tapes, slats, and bottom bar. In blinds equipped with escape-tight filters, in which the tilt-cord ends are evened up by running the gear segment out of mesh with the worm at blind-closed position, the ladder tape branches are wound about the tilt member to a greater degree in escaping the filter. Textile ladder tapes formed of various natural and synthetic fibers have sufficient stretch so that a blind may be completely closed even though the bottom bar is engaged by hold-down brackets and held against rising, the tapes again contracting when the slats are returned to level position.

Certain so-called "plastic" tapes in present use are formed of strips of soft sheet plastic material reinforced

2

internally by essentially nonstretchable strands, such as "Fiberglas" or "Fortesan" to render the tapes dimensionally stable. Such tapes are substantially nonstretchable. When using hold-down brackets of the type disclosed in

5 Patent 2,298,892 with a blind equipped with such tapes, not only is it very difficult to stretch the tapes sufficiently to engage the gudgeon pins of the bottom bar within the hold-down brackets, but, also, such a blind will resist closing since the tapes do not stretch sufficiently to permit the tape branches to be wound about the tilt member to the same degree as with textile tapes in closing the blind. Further, when the usual hold-down brackets are used, it is often impossible to "escape" the filter of such blinds.

15 The herein disclosed hold-down bracket of the present invention, which has its greatest utility in use with blinds in which the ladder tapes are substantially nonstretchable, is comprised of a unitary sheet metal strip formed to provide a gudgeon-pin-receiving portion which is generally oval in outline, the major dimension of the oval extending vertically. One side of the oval is open about midway of its height to permit the gudgeon pin of the bottom bar to be introduced within the oval, the relative diameter of the opening and the gudgeon pin being such that pressing the gudgeon pin against the opening will spread the opening slightly, the gudgeon pin then being retained against fortuitous disengagement.

The gudgeon pin is free to move both upwardly and downwardly within this portion of the hold-down bracket. 30 In such a construction, the gudgeon pin is free to rise somewhat when the slats are tilted to closed position and is free to drop somewhat in the event that the ladder tapes have been cut a fraction of an inch too long. In addition, the gudgeon pin is positively retained against fortuitous disengagement from the bracket, in all tilted positions of the slats of the blind.

35 Among the objects of the present invention are: to provide a hold-down bracket and installation which are particularly adapted for use with a blind equipped with substantially nonstretchable ladder tape, to provide a hold-down bracket and installation in which the gudgeon pin is retained in all tilted positions of the slats and in which the gudgeon pin will not have a tendency to creep out of the bracket on tilting the blind, and generally to improve hold-down brackets and installations of the type described.

40 Other objects and the nature and scope of the invention will be more apparent from the detailed description to follow.

45 My invention is clearly defined in the appended claims. In the claims, as well as in the description, parts may at times be identified by specific names for clarity and convenience, but such nomenclature is to be understood as having the broadest meaning consistent with the context and with the concept of my invention as distinguished from the pertinent prior art. The best mode in which I have contemplated carrying out my invention is illustrated in the accompanying drawings forming part of this specification, in which:

50 Fig. 1 is an isometric view of the lower-left corner of a Venetian blind and window frame, a portion of the window frame being broken away, and a hold-down bracket according to the present invention being used.

55 Fig. 2 is an isometric view of a hold-down bracket according to the present invention.

60 Fig. 3 is a side elevation of the hold-down bracket of Fig. 2.

65 Fig. 4 is a somewhat diagrammatic end elevation of a bottom bar engaged in the hold-down bracket according to the present invention, the bracket being shown in side elevation.

Fig. 5 is a view similar to Fig. 4, the bottom bar being shown in tilted position.

Fig. 6 is a view similar to Fig. 5, the bottom bar being shown tilted in the opposite direction.

Fig. 7 is a side elevation of a second form of bracket according to the present invention, for mounting on a vertical rather than on a horizontal surface.

Referring now to the drawings, Fig. 1 illustrates a typical hold-down bracket installation using the bracket of the present invention. A Venetian blind 10 is mounted in a window opening in an inside mount wherein the blind is suspended between the jamb surfaces of the window frame. The blind 10 is provided with a plurality of ladder tapes (one shown) having longitudinally extending tape branches 11, 11 for suspending the slats 12 and the bottom bar 14 of the blind. The bottom bar may be of the metal type having a plastic end cap 15 provided with a gudgeon pin 16 projecting from the mid-portion of the end cap. The gudgeon pin 16 preferably is cylindrical and about $\frac{1}{4}$ " in diameter. In order to improve the closure of the blind, the pin 16 may be located near the upper face of the bottom bar end cap 15.

Mounted on the sill 19 of the window opening and preferably with one edge against the jamb surface 20 of the opening is a hold-down bracket 21 according to the present invention. The hold-down bracket 21, which is better shown in Figs. 2 and 3, comprises a gudgeon-pin-receiving member 22 and a support member 24, the entire bracket being formed in one piece from a unitary strip of sheet metal.

The gudgeon-pin-receiving member 22 of the bracket is of generally oval outline, the major dimension of the oval extending substantially vertically. The shorter or minor dimension of the interior of the oval is slightly in excess of the diameter of the gudgeon pin 16 and the major dimension of the oval is preferably at least about twice the diameter of the gudgeon pin.

To provide for insertion of the gudgeon pin, the hold-down bracket 21 is formed in the shape shown in the drawings to form an opening 25 about midway of the height of one side of the oval. The opening 25 is defined by bights 26 and 27 formed by folding the intermediate portion and the end portion of the strip more or less back upon itself. The entire bracket is somewhat resilient and the opening 25 is slightly smaller than the diameter of the gudgeon pin 16, and is flaring on both sides of the narrowest portion thereof so as to be spread slightly to pass the gudgeon pin as it is pressed against the opening, either into or out of the oval.

The gudgeon-pin-receiving member 22 of the bracket is preferably formed with a cylindrical, downwardly-concave upper portion 29 and a cylindrical upwardly-concave lower portion 30 each having an inner radius slightly in excess of the radius of the gudgeon pin 16 and the two concave portions being connected together by a generally flat portion 31. The opposed, convex portions 26 and 27 defining the opening 25 are connected with the portions 29 and 30 by essentially straight portions 35 and 36, respectively. The portions 35 and 36 make sufficiently large angles with the horizontal so that, upon tilting the slats of the blind, the gudgeon pin will slip thereon and move toward the concave portion 29 or 30 as the case may be. Thus, the gudgeon pin does not engage the portions 29 and 30 with sufficient friction to creep or roll along and thereby possibly spread the opening 25 and release the gudgeon pin. It has been found that with plastic end caps and gudgeon pins in present-day use, an angle of at least 35° is sufficient.

The support member 24 of the bracket comprises an upstanding portion 37, which may be provided with a longitudinally extending corrugation or stiffening rib 39 and a mounting flange 40, the stiffening rib preferably extending into the mounting flange.

The mounting flange 40 extends horizontally and is provided with a pair of side flanges 41, 41 and an end

flange 42 coterminous with the side flanges. The mounting flange 40 is provided with a central hole 44 for reception of a screw for holding the bracket in position on the window sill 19. Preferably, the lower end of the end flange 42 is provided with a prong 45 which, upon tightening of the mounting screw, is forced into the surface on which the bracket is mounted to prevent the bracket from rotating about the screw.

The side edges 46 and 47 of the bracket 21, including the side flanges 41, 41 lie in two spaced, parallel, vertical planes. Accordingly, the bracket may be mounted with either side edge thereof closely adjacent either jamb surface 20 of a window opening, and the bracket is equally adaptable for mounting on either side, no rights or lefts being required.

In a proper installation, the bottom bar 14 of the blind will hang with the gudgeon pins 16 (one shown in the drawings) directly opposite the opening 25 of each hold-down bracket 21. If necessary, the support portion 24 of the bracket can be bent slightly to change its angle and thus adjust the height of the opening. With the gudgeon pins resting against the opposed convex portions 26 and 27 at the opening 25 of each bracket, pressure may be exerted by hand upon the bottom bar to cause the gudgeon pins to spread the opening slightly to admit the gudgeon pins within the pin-receiving member 22 of each bracket. The bracket is sufficiently resilient to resume its original contour when the gudgeon pin has entered the oval of the bracket.

In a blind in which the ladder tapes are of proper length, the gudgeon pin 16 will be supported directly opposite the opening 25 when the slats are level in blind-open position. Even though the blind may sway somewhat, the gudgeon pins will not strike or press against the convex portions 26 and 27 adjacent the openings 25 with sufficient force to spread the openings and release the gudgeon pins. Normal position is shown in Fig. 4.

If the ladder tapes of a blind should be cut a little long, the gudgeon pin 16 may be suspended a little lower than indicated in Fig. 4 when the slats are level, but the blind will still be supported against swaying, and the gudgeon pins retained within the hold-down brackets. There will be no slack in the ladder tapes caused by the bottom bar being supported by the hold-down brackets unless the tapes are cut so long that the gudgeon pins are resting on the cylindrical lower portions 30 of the brackets.

Upon tilting the slats of the blind 10 in either direction, the bottom bar 14 and end cap 15 will be rotated as indicated in Figs. 5 and 6. As the slats of the blind are rotated, the bottom bar will be raised slightly as the tape branches 11 on one face of the blind are raised and more or less wound up on the tilt member. As the bottom bar 14 is raised, the gudgeon pin 16 will approach the concave portion 29 of the pin-receiving member of the bracket until, in fully closed position of the slats, the gudgeon pins 16 may be pressed against the portion 29. However, the space provided for the rise of the gudgeon pin 16 in the closing of the blind is sufficient so that, even when nonstretchable ladder tapes are used, complete closure of the blind and even escapement of the tilt, such as disclosed in Nelson 2,174,994 of October 3, 1939, is permitted.

The second form of bracket shown in Fig. 7 is essentially the same as the bracket previously described and operates in a similar manner, similar reference characters being applied to the corresponding parts of the two brackets.

The bracket 49 of Fig. 7 has a gudgeon-pin-receiving member 22, which is similar in all respects to the gudgeon-pin-receiving member 22 of the bracket previously described. However, the support member 50 of the bracket 49 extends downwardly at an angle and then generally horizontally, and terminates in a vertically extending mounting flange 51 which may otherwise be similar to

the mounting flange 40 of the bracket previously described. Preferably, a corrugation or rib 52 extends longitudinally of the support portion 50 and into the mounting flange 51.

The bracket 49 is adapted for mounting on vertical surfaces and is used in the outside mounting of blinds, in which the blind is suspended from the face of a window frame rather than between the jamb surfaces, and when a blind is mounted on the face of a door. Inasmuch as the opening 25 of bracket 49 is about midway of the height of the gudgeon-pin-receiving member 22 of the bracket, the bracket may be mounted with equal facility with the mounting flange 51 extending downwardly from the pin-receiving member 22 of the bracket, as shown in the drawings, or the bracket may be inverted so that the flange extends upwardly therefrom as personal choice or the contour of the surface upon which the bracket is being mounted may dictate or require.

I claim:

1. In a Venetian blind organization in which the bottom bar of the blind is provided with gudgeon pins extending from the ends thereof and hold-down brackets are provided for receiving the gudgeon pins and holding the blind against substantial swinging movement, the improvement which comprises: each hold-down bracket having a hollow oval portion for receiving and retaining its associated gudgeon pin, the oval having about midway between its top and bottom a side opening of somewhat lesser height than the diameter of the gudgeon pin and providing for horizontal entry of the gudgeon pin into the oval with the bottom bar at normal level, the oval formation being sufficiently yieldable for the gudgeon pin to be forced horizontally sidewise through the side opening to locate the pin within the oval and the oval formation being sufficiently resilient to restore the side opening to approximately its original size and thereby hold the gudgeon pin against fortuitous disengagement from the oval, the shorter diameter of the oval being disposed substantially horizontally and being slightly in excess of the diameter of

the gudgeon pin and the longer diameter of the oval being disposed substantially vertically and being considerably in excess of the diameter of the gudgeon pin whereby the gudgeon pin may freely rise and fall in the oval as the slats of the blind are tilted.

2. The improvement as in claim 1 in which the bracket is of sheet metal and includes a body portion, the oval for receiving and retaining the gudgeon pin being adjacent to one end of the body portion, and the bracket having a mounting flange that extends from the other end of the body portion.

3. The improvement as in claim 2 in which the bracket is formed of an elongated strip of sheet metal which is recurved and provides a rounded nose at the bottom of the side-opening in the oval, and the mounting flange extends lengthwise from the body portion at an angle thereto.

4. The improvement as in claim 3 in which the strip is curved outwardly at the top of the side-opening in the oval and provides a rounded nose at the top of the side-opening.

5. The improvement as in claim 2 in which the bracket is formed of an elongated strip of sheet metal, the mounting flange extends at an angle to the body portion, and the respective longitudinal edges of the body portion, mounting flange and oval lie in common vertical planes.
